UNITED STATES PATENT OFFICE.

EUGENE J. MOYNIHAN, OF SAN FRANCISCO, CALIFORNIA.

DIPPER AND HANDLE FOR STEAM-SHOVELS.

1,285,318.

specification of Letters Patent. Patented Nov. 19, 1918.

Application filed February 25, 1918. Serial No. 219,146.

To all whom it may concern:

Be it known that I, EUGENE J. MOYNIHAN, a citizen of the United States, residing in the city and county of San Francisco and State of California, have invented a new and useful Improvement in Dippers and Handles for Steam-Shovels, of which the following is a specification.

My invention relates to improvements in steam shovels or the like wherein a cable engaging mechanism operates in conjunction with a dipper handle and dipper hingedly mounted thereon to invert said dipper.

The primary object of the present invention is to provide a dipper having means operatively connected thereto for inverting the dipper to dislodge boulders and the like which have become jammed into said dipper or whose dimensions are such that said boulder may not pass through the opened bottom of the dipper in the usual manner.

In the present state of the art steam shovels and excavators of like construction and operation have a dipper rigidly secured to the end of the dipper handle for ordinary excavating operations. This arrangement provides for scooping up dirt and other matter by operating a hoisting cable in conjunction with what is termed in the state of the art as crowding mechanism to move the dipper along the ground or against the face of an embankment to fill the dipper. After which the dipper is elevated by the cable and projected by the crowding mechanism over a receiving receptacle or conveyance and the excavated material released through the bottom of the dipper.

This type of dipper is incapable of being inverted for the purpose of dislodging boulders, or other objects too large to pass through the dipper.

Other arrangements of the operating mechanism and the dipper are provided wherein two and sometimes three operating lines or cables are connected to the dipper to drag the same along the ground, elevate it, and then invert it by the manipulation of a third cable to invert the dipper to release the contents therefrom. This type of mechanism is operated without the dipper handle.

The present invention provides a simple and effective attachment which may be readily secured to present standard types of

steam shovels operating with dipper and handle to readily invert the dipper without employing additional lines or cables and mechanism for their operation, and which will not effect or interfere with the usual manner of operation.

I accomplish these and several other objects by means of the device disclosed in the drawings forming a part of the specification wherein like characters of reference are used to designate similar parts throughout the said specification and drawings, and in which—

Figure 1 is a side elevation of a steam shovel, partly broken, disclosing my improvement attached thereto;

Fig. 2 is an enlarged side elevation of the boom, dipper handle and dipper in the usual position for excavating purposes, disclosing the arrangement of my improvement;

Fig. 3 is a plan view of the dipper and end of the dipper handle;

Fig. 4 is a view similar to Fig. 2 but disclosing the dipper inverted to release a boulder;

Fig. 5 is a plan view of the cable engaging means for preventing the lowering of the dipper handle when the dipper is released;

Fig. 6 is a rear elevation, on an enlarged scale, of a standard type of dipper with my improvement attached thereto; and

Fig. 7 is a broken side elevation of Fig. 6 disclosing the method of mounting the bucket to the dipper handle.

Referring to the drawings the numeral 1 is used to designate a standard type of dipper having bearings 2 in the rear surface thereof to receive bolts 3 also engaged by a bracket 4 rigidly secured to the end of a dipper handle 6.

The upper surface of the dipper handle 6, adjacent the end of said handle, is provided with a casting or block 7 having a bolt 8 to engage the ends of offset links 9, the other ends of said links 9 in the usual practice, are rigidly connected between lugs 11 formed integral with the back of the dipper 1 and adjacent each side thereof. Therefore, in the present state of the art, the links 9 and the bearings 2, bolts 3 and bracket 4 form shackles by means of which the dipper 1 is at all times rigidly fixed and not hingedly, secured to the end of the dipper handle 6.

In my invention the ends of the links 9

merely bear or impinge against bolts 10 passing through the lugs 11, the purpose of which will hereinafter be more fully set forth, and said links 9 are provided with 5 pins 12 which ride in slots 14 within offset plates 16 whose upper offset ends are secured on each side of the lugs 11 whereby adjacent faces or surfaces of the plates 16 form a channel equal in width to the space 10 between the lugs 11 and slightly larger than the thickness of the links 9, thereby leaving the dipper 1 hingedly mounted upon the end of the dipper handle 6 by means of the bearings 2, bolts 3 and bracket 4 secured to 15 said dipper end 6.

The plates 16 are further secured to the back of the dipper 1 by means of the hinge bolts 17 of the hinges 18 on the swinging bottom 19 of the dipper 1, said bottom 19 20 being normally held in a closed position by the usual latch 21.

The ends of the links 9 are rigidly held in the usual operative position by the tension of the hoisting cable 22 passing from 25 the hoisting mechanism 23 within the cab 24 over sheave 27 on the end of a boom 28, through the sleeve block 29 secured to the bail 31 of the dipper 1 and thence over an idler 26 on the boom 28 to the end of the 30 dipper handle 6.

As the dipper 1 is of considerably greater weight than the dipper handle 6 it is evident that the tension of the cable 22 will impinge the back of the dipper 1 35 against the free or outer ends of the links 9.

The links 9 are further secured in such position by means of latches 32 secured to a shaft 33 having a crank portion 34 engaged by a suitable spring 36 whose other 40 end is secured to the back of the dipper 1 to normally retain the ends of the latches 32 within the path of the pins 12 on the ends of the links 9 to prevent the said pins 12 from traversing the slots 14 in the plates 16, 45 thereby providing rigidity between the dipper 1 and the handle 6 when used in the ordinary manner for excavating purposes.

It will be observed that the cable 22 is 50 substantially continuous from the hoisting mechanism 23 to the dipper handle 6. If the hoisting mechanism pays the cable 22 out the weight of the dipper 1 and dipper handle 6 will cause them to be lowered. If, however, the latches 32 are released to 55 permit the dipper 1 to swing freely on the bolts 3, and the cable 22 is rigidly engaged, by locking the idler 26 to prevent the lowering of the dipper handle 6, when said cable 22 is paid out or released, the dipper 1 will 60 swing on the bolts 3, which then serve as hinges, and the said dipper 1 is inverted a degree in proportion to the amount of cable paid out as disclosed in Fig. 4 of the drawings.

65 I find from experiment, however, that it

would be difficult to rigidly engage a portion of the cable 22 by merely passing the same over one idler as at 26.

In order to effectively engage that portion of the cable 22 controlling the dipper handle 6 to prevent lowering of said handle when the dipper 1 is to be inverted, and yet provide in effect a continuous operating cable of what is known as the "three reaved type," I have provided on each side of the idler 26 a pair of drums 37 and 38 rigidly secured to a shaft 39, upon which the idler 26 is loosely mounted, said shaft 39 being rotatably mounted upon the top of the boom 28 and having a pair of oppositely faced 80 ratchets 41 and 42 on one end thereof.

A pair of pawls 43 and 44 are mounted to engage the ratchets 41 and 42 and are normally held from such engagement by means of a weighted arm 46. The pawls 43 85 and 44 may be operated to engage the ratchets 41 and 42 to prevent the rotation of the drums 37 and 38, by means of a line 47 operatively connected to a foot pedal 49 adjacent the operator.

The line or cable 22 then stops or ends upon the drum 37 and a short cable 51 is wound in the same direction upon the drum 38 and leads off to the end of the dipper handle 6 thereby forming substantially and 95 in effect a continuous cable from the hoisting mechanism 23 to the end of the dipper handle 6. It is obvious that as the cable 22 unwinds from the drum 37 the drum 38 will be rotated to take up the cable 51 thereby 100 providing in effect a single cable as herein-before set forth.

To release the latches 32 I have provided a line 52 connected to the crank portion 34 of the latch shaft 33 and also to the usual 105 dump lever 53 pivotally suspended from the handle 6 and having a line 54 to the cab 24 or near the operator.

A second line 56, shorter than the line 52, is also secured to the lever 53 and to the 110 latch 21 to release the bottom 19 of the dipper 1.

As the line 56 is shorter than the line 52 it is evident that the bottom 19 will be released before the longer line 52 operates 115 to release the latches 32. Therefore the dipper 1 and handle 6 therefor may be operated in the usual manner without releasing the links 9.

The operation is as follows:

120 The dipper 1 and handle 6 are operated in excavating by means of the cable 22 and its extension 51 in the usual manner.

When a boulder is encountered whose dimensions will not permit its passage through 125 the dipper 1 in the usual manner said boulder is elevated on the dipper 1, or partly within it as disclosed in Fig. 1 of the drawings.

By means of the crowding mechanism, in- 130

dicated in general by the numeral 50, the dipper 1 and handle 6 are projected over a receiving receptacle or flat car, indicated as at 55 in Fig. 4 of the drawings.

5 The lines 54 and 52 are then operated to release the latches 32 in the path of the pins 12 on the links 9, the line 56 being also operated to release the bottom 19 but as the boulder can not pass through the

10 dipper 1 the latter releasing is unessential. The tension on the cables 22 and 51 is still maintained by the weight of the dipper 1, handle 6 and the boulder so that the ends of the links 9 still impinge on the back 15 of the dipper 1 as disclosed in Fig. 7 of the drawings.

The foot lever 49 is operated to actuate the line 47 and move the pawls 43 and 44 into engagement with the ratchets 41 and 20 42 to prevent the rotation of the drums 37 and 38 and the paying out of the cable 51 supporting the handle 6.

If the cable 22 is now released or paid out by the hoisting mechanism 23 the dipper 1 is rotated on the bolts 3, which serve as hinges, and the said dipper 1 is gradually inverted to deliver the boulder onto the flat car 55 or other receiving receptacle as disclosed in Fig. 4 of the drawings.

30 After the boulder has been delivered the dipper 1 may be automatically restored to normal position for normal digging or excavating operations by taking in the line 22. As both pawls 43 and 44 engage both 35 oppositely faced ratchets 41 and 42 respectively, it is evident that the line 51 and the dipper handle 6 can not be moved until said pawls are released.

As the line 22 is taken in the dipper 1 40 is elevated or restored to normal position, the pins 12 on the links 9 meanwhile traversing the slots 14 of the plates 16 until the upper ends of said slots 14 are encountered. The latches 32 are returned to normal position behind or beneath the pins 12, as the case may be, and held in such position by the tension of the spring 36.

When the dipper 1 has been returned to normal position the pawls 43 and 44 are 45 released from the ratchets 41 and 42 respectively and held from engaging relation by means of the weighted arm 46 as disclosed in Figs. 1 and 2 of the drawings.

The lines 22 and 51 will now operate as 50 a single continuous line and normal excavating operations may be resumed.

It is obvious from the above that I have 55 provided an improved attachment for steam shovels and the like wherein the dipper 1 may be inverted to deliver the contents thereof without interfering with the present operation.

The only additional mechanisms required 60 are the plates 16 and the means for releasing the links 9 and for rigidly engaging a por-

tion of the operating cable and withholding the same temporarily from operation.

Having thus described my invention what I claim as new and desire to secure by Letters Patent is—

70 1. The combination with a steam shovel of a dipper handle; a dipper hingedly mounted upon the dipper handle; an operating cable connected to the dipper and to the handle; and means for engaging the operating cable to prevent the lowering of the dipper handle only when said cable is paid out whereby the dipper may be inverted.

75 2. The combination with a steam shovel of a dipper handle; a dipper hingedly mounted upon the dipper handle; an operating cable connected to the dipper and to the handle; and means for engaging the operating cable to prevent the lowering of the dipper handle only when said cable is paid out whereby the dipper may be inverted; and means for automatically securing the dipper rigidly to the handle when said dipper is returned to normal position relatively to said handle.

80 3. The combination with a steam shovel of a dipper handle; a dipper hingedly mounted upon the dipper handle; an operating cable connected to the dipper and to the handle; and means for engaging the operating cable to prevent the lowering of the dipper handle only when said cable is paid out whereby the dipper may be inverted; and means for automatically securing the dipper rigidly to the handle when said dipper is returned to normal position relatively 85 to said handle; and means for releasing the dipper securing means.

90 4. In a steam shovel, the combination 95 with a cable boom of a dipper handle mounted thereon; a dipper hingedly mounted upon one end of the dipper handle; an operating cable connected to the dipper and to the dipper handle; means for detachably securing the dipper rigidly to the handle; means for releasing the dipper securing means; and means for engaging the operating cable to prevent the lowering of the dipper handle when said cable is paid out whereby the dipper may be inverted.

100 5. In a steam shovel, the combination 105 with a dipper handle of a dipper hingedly mounted upon one end of said handle; a pair of links pivotally mounted upon the handle and slidably connected to the dipper; means for preventing a movement of the links on the dipper to secure the same rigidly to the handle; means for releasing the dipper securing means to permit a movement 110 of the dipper on its hinge; an operating cable connected to the dipper and to the handle; and means for engaging the cable

115 to prevent a movement of the dipper handle when the cable is paid out whereby the dipper may be inverted.

6. In a steam shovel or the like, the combination with a dipper handle of a dipper hingedly mounted upon one end of said handle; slotted plates secured to the rear 5 of the dipper; a pair of links pivotally mounted upon the dipper handle and slidably engaging the slots within the slotted plates; means for normally preventing a movement of the links within the slots to 10 rigidly secure the dipper to the handle; means for releasing the dipper securing means to permit a movement of the dipper upon its hinge and relatively to the handle; an operating cable connected to the dipper 15 and to the dipper handle; and means for engaging a portion of the operating cable to prevent a movement of the dipper handle whereby the dipper may be inverted when the cable is paid out to lower the dipper. 20

7. In a steam shovel, the combination with a cable boom of a dipper handle movably mounted thereon; a dipper hingedly mounted upon one end of the handle; a pair 25 of slotted plates detachably mounted upon each side of the rear of the dipper; a pair of offset links pivotally mounted upon the end of the handle adjacent the dipper and slidably engaging the slots in the plates to 30 permit a movement of the dipper relatively to the handle; a pair of latches arranged to normally prevent a movement of the links within the slots to rigidly secure the dipper to the handle; means for releasing the 35 latches to permit a movement of the dipper relatively to the handle; a pair of sheaves connected together and rotatably mounted upon the cable boom; an operating cable connected to the dipper and to one of the 40 sheaves; a second cable connected to the remaining sheave and to the dipper handle, said cables and sheaves operating in unison to provide a continuous cable and to operate the dipper and the handle therefor 45 when the dipper securing latches secure the dipper to the handle; and means for preventing a movement of the sheaves when the securing latch is released and the cable is paid out whereby the handle may be held 50 against movement and the dipper inverted.

8. In a steam shovel, the combination with a cable boom of a dipper handle movably mounted thereon; a dipper hingedly mounted upon one end of the dipper handle; a pair of slotted plates detachably mounted upon each side of the rear of the dipper; a pair of offset links pivotally mounted upon the end of the handle adjacent the dipper and slidably engaging the 55 slots in the plates to permit a movement of the dipper relatively to the handle; a pair of latches arranged to normally prevent a movement of the links in the slots and the dipper relatively to the handle; means for releasing the latches to permit 60

a movement of the dipper relatively to the handle; a pair of sheaves connected together and rotatably mounted upon the cable boom; an operating cable connected to the dipper and to one of the sheaves; a second cable connected to the remaining sheave and to the dipper handle, said cables and sheaves operating to provide a continuous cable and to operate the dipper and handle therefor simultaneously when the dipper securing latches are in normal position; a pair of oppositely faced ratchets secured to the sheaves; and means for engaging the ratchets to prevent a rotation of the sheaves and a movement of the dipper when the operating cable is paid out and the dipper securing latches released whereby the dipper may be inverted. 75 80

9. In a steam shovel, the combination with a cable boom of a dipper handle movably mounted thereon; a dipper hingedly mounted upon one end of the dipper handle; a pair of slotted plates detachably mounted upon each side of the rear of the dipper; a pair of offset links pivotally mounted upon the end of the handle adjacent the dipper and slidably engaging the slots in the plates to permit a movement of the dipper relatively to the handle; a pair of latches arranged to normally prevent a movement of the links in the slots and the dipper relatively to the handle; means for releasing the latches to permit a movement of the dipper relatively to the handle; a pair of sheaves connected together and rotatably mounted upon the cable boom; an operating cable connected to the dipper and to one of the sheaves; a second cable connected to the remaining sheave and to the dipper handle, said cables and sheaves operating to provide a continuous cable and to operate the dipper and handle therefor simultaneously when the dipper securing latches are in normal position; a pair of oppositely faced ratchets secured to the sheaves; and means for engaging the ratchets to prevent a rotation of the sheaves and a movement of the dipper when the operating cable is paid out and the dipper securing latches released whereby the dipper may be inverted. 95 100

10. In a steam shovel, the combination with a cable boom of a dipper handle movably mounted thereon; a dipper hingedly mounted upon one end of the handle; means for rigidly securing the dipper to the handle; means for releasing the dipper securing means; a pair of connected sheaves rotatably mounted upon the cable boom; an operating cable connected to the dipper and to one of the sheaves; a second cable connected to the remaining sheave and to the 115 120 125 130

dipper handle; and means for preventing a rotation of the sheaves to prevent a movement of the dipper handle when the operating cable is paid out whereby the dipper 5 may be inverted.

11. In a steam shovel, the combination with a cable boom of a dipper handle movably mounted upon said boom; a dipper hingedly mounted upon one end of the dipper 10 handle; means for rigidly securing the dipper to the handle; means for releasing the dipper securing means; a pair of connected sheaves rotatably mounted upon the boom; an operating cable connected to the dipper and to one of the sheaves; a second cable connected to the remaining sheave and 15 to the dipper handle, said sheaves and cables

operating to provide a continuous cable to actuate the dipper and handle therefor simultaneously; a pair of oppositely faced 20 ratchets secured to the sheaves; a pair of pawls for engaging the ratchets; means for normally preventing the engagement of the pawls with the ratchets; and means for moving the said pawls into engagement 25 with the ratchets to prevent a rotation of the sheaves whereby a movement of the dipper handle may be prevented when the operating cable is paid out to lower the dipper thereby inverting said dipper. 30

In witness whereof I have hereunto set my signature.

EUGENE J. MOYNIHAN.
